UNITED STATES PATENT OFFICE

HARRY B. GOLDMAN, OF BROOKLINE, PENNSYLVANIA

ELECTROHYDRAULIC SYSTEM FOR ELEVATOR BRAKES AND THE LIKE

Application filed November 9, 1928. Serial No. 318,137.

My invention is particularly designed for the operation of brakes for controlling elevators, although it is susceptible of other uses.

The principal object of my invention is to provide a new brake system for replacing less desirable brake systems, and particularly for replacing the alternating-current electromagnets for releasing the brakes in alternating-current elevator installations.

10 In electric elevator installations, it is customary to provide a spring-actuated brake which is normally applied to a driving shaft of the elevator and which is released by an electromagnet, which is energized whenever the main elevator motors are energized in either direction, and which is deenergized when the control switch in the elevator car is returned to its mid-position or, in general, when the main elevator motors are deenergized.

15 Alternating-current brake-releasing magnets which are available for use in alternating-current elevator systems invariably involve the use of dashpots which are notoriously unreliable; they are exceedingly noisy, grippy in their action, not readily adjustable, and liable to burn out if they stick when the armature is not in engagement with its pole-pieces, besides being unwarrantably high in cost.

20 In direct-current elevator installations, less trouble is experienced with the direct-current brake-releasing magnets, but they are still subject to many objections, principal among which may be mentioned their high cost.

25 It has been proposed, heretofore, to provide a motor which is constantly running whenever the elevator is in condition for operation, whether it is standing still or moving, and to utilize such motor for energizing the brake-controlling equipment of the elevator. Such systems are practically out of the question, however, on account of the losses, in power and depreciation, resulting from the continuous operation of the said motor even when the elevator is long idle, as it may be for long intervals during the day.

30 My invention overcomes the foregoing and other difficulties by providing a system where-
35 by a motor for energizing the brake-control-

ling equipment is energized only when the main elevator motors are energized.

More particularly, my invention provides a combined electrical and hydraulic or pneumatic brake-controlling system in which a pump is connected to the motor which is energized only when the brake is to be released; and any suitable piston, bellows or diaphragm arrangement is utilized for responding to the hydraulic pump-pressure to force open the brake-shoes against the action of their closing spring.

35 A further object of my invention is to provide means for quickly stopping, or even temporarily reversing, the motor which actuates the brake-controlling equipment.

With the foregoing and other objects in view, my invention consists in the apparatus, systems and circuit arrangements hereinafter described and claimed and illustrated in the accompanying drawing, wherein

40 The single figure is a diagrammatic view, showing parts in section, illustrating a preferred embodiment of my invention.

45 As shown in the drawing, my invention is applied to an elevator brake 5 comprising two brake-shoes 6 bearing on a break wheel or pulley 7 mounted on the main elevator drive shaft 8. The brake shoes are mounted on brake beams 9 which are drawn together by means of a brake-actuating spring 11 which normally biases the brake 5 to its closed or applied position.

50 The means for controlling the operation of the elevator brake is actuated by means of an electric motor 12, which is shown as a three-phase squirrel-cage motor, and which is adapted to be operated when the brake is released from its clamping engagement with the brake wheel or pulley, said motor being adapted to be stopped when the brake is to be applied by means of its actuating spring.

55 The motor drives a pump 13 which is preferably of a type which has the inherent characteristic of maintaining a predetermined limited static pressure-head during its operation. For this purpose, some types of centrifugal pumps have been found very satisfactory, as shown in the drawing, although care has to be taken, in the selection of a cen-

trifugal pump, to avoid those pumps which will not develop any pressure-head against a static load, or when the movement of the liquid through the pump is blocked. In general, a pump such as that just mentioned, 5 comprises an impeller mounted on a rotating shaft, as is well known in the art.

The pump 13 draws the oil or other liquid from a reservoir 14 and applies it, under suitable pressure, to a hydraulic brake cylinder 15, where a suitable arrangement of pistons, 10 bellows or diaphragms is provided for actuating a pair of plunger-rods 17 through a sufficient distance to release the brake. As shown in the drawing, rubber diaphragms 18 15 are provided, which press against plunger-heads 19 carried by the plunger-rods 17. The length of the plunger stroke, and hence the force applied to the brake, may be regulated by means of a threaded collar 21, and the operation may be still further adjusted by controlling the loose play between the plunger-rods 17 and the brake arms 9, as by means of 20 adjusting-bolts 22 on the ends of the plunger-rods 17.

In operation, the hydraulic pump 13, as soon as it is rotated, withdraws a small quantity of oil or other liquid from the reservoir 14 and applies it at considerable pressure, 30 through a discharge pipe 24 which connects the pump 13 and the hydraulic brake cylinder 15, forcing out the plunger rods 17 against the brake beams 9, and reducing the oil level in the reservoir to a position such as indicated by dotted lines 26.

In a system such as that just described, it is usually necessary to provide means for expediting the release of the hydraulic pressure when the motor 12 is deenergized, as the motor has considerable inertia, and the brakes 40 must be applied with as little delay as possible, particularly where "inching" must be resorted to, in leveling the elevator car with respect to the floors of the building.

In the drawing, I have shown a preferred 45 means for expediting the releasing of the brake-opening means, which consists in quickly stopping the motor 12, or even temporarily reversing the same. The motor is normally controlled by means of an electromagnetic 50 switch or relay 27 having main contacts 28 which energize the motor in the forward direction whenever the relay is actuated to closed position.

According to the system shown in the drawing, back contacts 29 are provided on the electromagnetic relay 27, so that whenever the relay is deenergized, the back contacts are closed 55 for reversing the motor 12. Additional 60 means are provided, however, for preventing the energization of the motor in the reverse direction, except when the elevator-brake is in its open or released position with the shoes 65 out of engagement with the brake wheel or pulley 7. Such additional means is shown

as a switch 31 which is mechanically operated in accordance with the position of the plunger-rods 17 of the hydraulic plunger mechanism, as by means of a collar 32 on the right-hand plunger-rod 17, engaging an actuating lever 33 on the switch 31.

The electrical operation of the system shown in the drawing is as follows. The electromagnetic relay 27 is actuated by any suitable means, which is intended to be symbolized by the push-button 34, although, in general, it will be understood that the energizing circuit of this relay is coupled to the main elevator motors (not shown) or to the controller in the elevator car (not shown) 80 so as to be energized when the control handle is in either the forward or the reverse position, and deenergized when the control handle is in its mid-position.

When the electromagnetic relay 27 closes, 85 it energizes the pump motor 12 in its normal pumping or forward direction and, as full voltage is immediately applied to the motor, it accelerates almost instantaneously to its full speed and causes the pump to immediately develop sufficient oil-pressure to retract the brake shoes and thus to release the 90 brake from the main elevator drive shaft 8 against the force of the spring biasing means 11.

It will be understood that, when the brake is released, the mechanically-coupled switch 31 in the reversing circuit of the motor is closed, but nothing happens because this reversing circuit also includes the back-contacts 29 on the electromagnetic relay 27, which are open whenever the relay is in its energized 100 position.

When the electromagnetic switch 27 is de-energized, the normal energizing circuit of the pump-motor 12 is interrupted, and the back-contacts 29 of the relay close, so as to apply full line-voltage to the motor 12, in reverse phase-sequence, thus almost instantaneously stopping the motor and starting it 110 rotating a few revolutions in the reverse direction. The temporary reverse rotation of the motor is desirable in order to facilitate the flow of the oil from the hydraulic brake cylinder 15 back into the reservoir 14, thus 115 quickly deenergizing the pistons 17 of the hydraulic mechanism. This is necessary because the restricted openings in the pump 13 would otherwise retard the back flow of oil through it if the pump were not reversed, and 120 would thus retard the return of the brake shoes to their normal biased position in engagement with the brake wheel 7. It will be understood that only a small quantity of oil need be passed through the pump, but it 125 is essential that this be done as quickly as possible in order to quickly apply the brake.

As soon as the brake 5 is again applied to the brake wheel or pulley 7, the mechanically-actuated switch 31, engaging the collar 1

32 on the plunger-rod 17 of the hydraulic mechanism, opens, thus deenergizing the pump motor 12.

While I have illustrated means for momentarily reversing the pump, in order to expedite the return of oil from the hydraulic pressure-cylinder 15 to the reservoir 14, it is to be understood that any other suitable means for performing this function may be utilized, although, at present, I prefer the means shown in the drawing.

It will be seen, from the foregoing description, that I have developed a particularly quiet brake which is capable of developing enormous pressures almost instantaneously, in a mechanism embodying the utmost in simplicity and reliability, developing not a single defect or failure even after a quarter of a million operations in the test laboratory.

20 While I have illustrated my invention in a preferred embodiment, I wish it to be understood that such illustration is intended only to be suggestive, and not as limiting my invention to the particular embodiment shown.

25 I desire, therefore, that the appended claims shall not be limited except as required by the language thereof when read in the light of the prior art.

I claim as my invention:

30 1. The combination with a movable element normally biased to one position, of an electric motor adapted to be operated when said element is to be retracted to a different position and stopped when said element is in its biased position, means for starting and stopping said motor, means responsive to the rotation of said motor for developing a force and applying it in such manner as to move said element to said retracted position, and means for applying a force bringing said motor to a quick stop when said element is to be returned to its biased position.

2. The combination with a movable element normally biased to one position, of a reversible electric motor adapted to be operated when said element is to be retracted to a different position and stopped when said element is in its biased position, means for starting and stopping said motor, means responsive to the rotation of said motor for developing a force and applying it in such manner as to move said element to said retracted position, and means for momentarily reversing said motor when said element is to be returned to its biased position, whereby said force-developing means may be more quickly moved so as to allow the biasing means to more quickly return said element to its biased position.

3. The combination with a movable element normally biased to one position, of a reversible electric motor adapted to be operated when said element is to be retracted to a different position and stopped when said element is in its biased position, means for starting and stopping said motor, means re-

sponsive to the rotation of said motor for developing a force and applying it in such manner as to move said element to said retracted position, and means for momentarily reversing said motor when said element is to be returned to its biased position, whereby said force-developing means may be more quickly moved so as to allow the biasing means to more quickly return said element to its biased position, said reversing means including means responsive to the return of said element for interrupting the reversing circuit of the motor.

4. The combination with a movable element normally biased to one position, of an electric motor adapted to be operated when said element is to be retracted to a different position and stopped when said element is in its biased position, means for starting and stopping said motor, retracting means responsive to the rotation of said motor for developing a force and applying it in such manner as to move said element to said retracted position, and auxiliary means operative at the moment of the interruption of the normal energizing circuit of said motor to develop a reverse force and apply the same to said retracting means, whereby the biasing means may more quickly return said element to its normal position.

5. An electro-hydraulic brake system comprising a spring-applied brake, an electric motor, means for energizing and deenergizing the motor, a hydraulic pressure-responsive means for releasing said brake, a liquid reservoir, and an impeller pump driven by said motor and connected between said reservoir and said hydraulic pressure-responsive means, said pump itself inherently having the characteristic of maintaining a predetermined limited static pressure-head during its operation.

6. An electro-hydraulic brake system comprising a spring-applied brake, an electric motor, a switch for energizing and deenergizing the motor, a hydraulic pressure-responsive means for releasing said brake, a liquid reservoir, an impeller-type pumping apparatus driven by said motor and connected between said reservoir and said hydraulic pressure-responsive means, said pumping apparatus itself having the characteristic of maintaining a predetermined limited static pressure-head during its operation, and auxiliary means operative at the moment of the interruption of the normal energizing circuit of said motor to expedite the return of the liquid from said pressure-responsive means to said reservoir.

7. An electro-hydraulic brake system comprising a spring-applied brake, an electric motor, a switch for energizing and deenergizing the motor, a hydraulic pressure-responsive means for releasing said brake, a liquid reservoir, an impeller-type pump driven by said motor and connected between said

reservoir and said hydraulic pressure-responsive means, said pump having the characteristic of maintaining a predetermined limited static pressure-head during its operation, 5 and means for bringing said motor to a quick stop when the brake is to be applied.

8. An electro-hydraulic brake system comprising a spring-applied brake, a reversible electric motor, a switch for energizing and deenergizing the motor, a hydraulic pressure-responsive means for releasing said brake, a liquid reservoir, a pumping apparatus driven by said motor and connected between said reservoir and said hydraulic pressure-responsive means, said pumping apparatus having the characteristic of maintaining a predetermined limited static pressure-head during its operation, and auxiliary means operative at the moment of the interruption of the normal energizing circuit of 10 said motor to momentarily reverse said motor.

9. An electro-hydraulic brake system comprising a spring-applied brake, a reversible electric motor, a switch for energizing and deenergizing the motor, a hydraulic pressure-responsive means for releasing said brake, a liquid reservoir, a pump driven by said motor and connected between said reservoir and said hydraulic pressure-responsive means, auxiliary means operative at the moment of the interruption of the normal energizing circuit of said motor to momentarily reverse said motor, said reversing means 35 including means responsive to the re-application of the brake for interrupting the reversing circuit of the motor.

10. The combination with a movable element normally biased to one position, of an 40 electric motor adapted to be operated when said element is to be retracted to a different position and stopped when said element is in its biased position, means for starting and stopping said motor, means responsive to the rotation of said motor for developing a force 45 and applying it in such manner as to move said element to said retracted position, said last-mentioned means comprising: a pump actuated by said motor, means responsive to the pump-pressure for moving said element to said retracted position and holding it there against the action of its biasing means, and means for applying a force bringing said 50 motor to a quick stop when said movable element is to be returned to its biased position.

11. The combination with a movable element normally biased to one position, of an 60 electric motor adapted to be operated when said element is to be retracted to a different position and stopped when said element is in its biased position, means for starting and stopping said motor, means responsive to the rotation of said motor for developing a force 65 and applying it in such manner as to move

said element to said retracted position, said last-mentioned means comprising: a pump actuated by said motor, means responsive to the pump-pressure for moving said element to said retracted position and holding it there 70 against the action of its biasing means, and auxiliary means operative immediately upon the interruption of the normal energizing circuit of said motor to apply a reverse liquid pressure, thereby expediting the flow of fluid 75 from said pump-pressure-responsive means.

12. The combination with a movable element normally biased to one position, of a reversible electric motor adapted to be operated when said element is to be retracted to 80 a different position and stopped when said element is in its biased position, means for starting and stopping said motor, means responsive to the rotation of said motor for developing a force and applying it in such 85 manner as to move said element to said retracted position, said last-mentioned means comprising: a pump actuated by said motor, means responsive to the pump-pressure for moving said element to said retracted position and holding it there against the action 90 of its biasing means, and means operative at the moment of the interruption of the normal energizing circuit of said motor to reverse said motor.

13. The combination with a movable element normally biased to one position, of a reversible electric motor adapted to be operated when said element is to be retracted to a different position and stopped when said element is in its biased position, means for starting and stopping said motor, means responsive to the rotation of said motor for developing a force and applying it in such manner as to move said element to said retracted position, said last-mentioned means comprising: a pump actuated by said motor, means responsive to the pump-pressure for moving said element to said retracted position and holding it there against the action 100 of its biasing means, means operative at the moment of the interruption of the normal energizing circuit of said motor to reverse said motor, and means operative upon the return of said element to its normal biased position for interrupting the reversing circuit of the motor.

14. The combination with a movable element normally biased to one position, of an electric motor adapted to be operated when said element is to be retracted to a different position and stopped when said element is in its biased position, means for starting and stopping said motor, retracting means responsive to the rotation of said motor for moving said element to a different position, and auxiliary means, coming into operation at the moment of the interruption of the normal energizing circuit of said motor and while the motor still has considerable speed, 115 120 125 130

to produce and apply a force in a direction to deenergize said retracting means.

15. The combination with a movable element normally biased to one position, of an electric motor adapted to be operated when said element is to be retracted to a different position and stopped when said element is in its biased position, means for starting and stopping said motor, retracting means responsive to the rotation of said motor for moving said element to a different position, and auxiliary means, initially coming into operation at the moment of the interruption of the normal energizing circuit of said motor and while the motor still has considerable speed, to derive a force from said motor tending to expedite the movement of the retracting means to normal deenergized position.

16. The combination with a movable element normally biased to one position, of an electric motor adapted to be operated when said element is to be retracted to a different position and stopped when said element is in its biased position, means for starting and stopping said motor, retracting means responsive to the rotation of said motor for moving said element to a different position, said last-mentioned means comprising: an impeller pump actuated by said motor, said pump itself inherently having the characteristic of maintaining a predetermined limited static pressure-head during its operation, means responsive to the pump-pressure for moving said element to said retracted position and holding it there against the action of its biasing means, and auxiliary means operative at the moment of the interruption of the normal energizing circuit of said motor to quickly pass the fluid from said pump-pressure responsive means.

17. A hydraulic system comprising a prime mover, an impeller pump driven thereby, said pump itself having the characteristic of maintaining a predetermined limited pressure-head during its operation, a pressure-responsive device, and means for applying said pump pressure head to said pressure-responsive device.

18. An electro-hydraulic brake system comprising a brake, an electric motor, means for energizing and deenergizing the motor, a hydraulic pressure-responsive means for actuating said brake, a liquid reservoir, and an impeller pump driven by said motor and connected between said reservoir and said hydraulic pressure-responsive means, said pump itself inherently having the characteristic of maintaining a predetermined limited static pressure-head during its operation, the rotors of the pump and motor being rigidly mounted on the same shaft.

19. An electro-hydraulic brake system comprising a brake, an electric motor, means for energizing and deenergizing the motor, a hydraulic pressure-responsive means for

actuating said brake, and an impeller pump driven by said motor and connected to said hydraulic pressure-responsive means, said pump itself inherently having the characteristic of maintaining a predetermined limited static pressure-head during its operation.

In testimony whereof, I have hereunto subscribed my name this 7 day of November, 1928.

HARRY B. GOLDMAN.
